INVENTOR
HAIG PATIGIAN

BY J. M. Wright,

ATTY.

UNITED STATES PATENT OFFICE.

HAIG PATIGIAN, OF SAN FRANCISCO, CALIFORNIA, ASSIGNOR TO NATIONAL COMMITTEE FOR ARMENIAN AND SYRIAN RELIEF, OF NEW YORK, N. Y.

DESIGN FOR A BADGE.

51,734.

Specification for Design.

Patented Feb. 5, 1918.

Application filed December 3, 1917. Serial No. 205,267. Term of patent 3½ years.

To all whom it may concern:

Be it known that I, HAIG PATIGIAN, a citizen of the United States, residing at San Francisco, in the county of San Francisco and State of California, have invented a new, original, and ornamental Design for Badges, of which the following is a specification, reference being had to the accompanying drawing, forming part thereof.

The figure is a plan view of a badge, showing my new design.

I claim:

The ornamental design for a badge, as shown.

HAIG PATIGIAN.

Witnesses:

FLORA HALL,
S. ANDERSON.
